UNITED STATES PATENT OFFICE.

EMMET JOPLING BONDURANT, OF ATHENS, GEORGIA, ASSIGNOR TO GEORGIA PLOW & FOUNDRY CO., OF ATHENS, GEORGIA.

PROJECTILE.

1,218,832.

Specification of Letters Patent. Patented Mar. 13, 1917.

Application filed June 3, 1916. Serial No. 101,596.

To all whom it may concern:

Be it known that I, EMMET J. BONDURANT, a citizen of the United States, residing at Athens, in the county of Clarke and State of Georgia, have invented a new and useful Projectile, of which the following is a specification.

This invention relates to a projectile particularly designed for use in cutting away entanglements of wire, and for like purposes, one of the objects of the invention being to provide a projectile having combined with it cutting elements which are normally housed but which are automatically released while the projectile is in flight, thus to move outwardly beyond the periphery of the projectile so as to come into engagement with and sever any wire entanglements or the like into which the projectile may be propelled.

With the foregoing and other objects in view which will appear as the description proceeds, the invention resides in the combination and arrangement of parts and in the details of construction, hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:

Figure 1 is a central longitudinal section through the projectile, the outwardly extended position of one of the cutting blades being indicated by dotted lines.

Fig. 2 is an enlarged section on line A—B Fig. 1.

Fig. 3 is an enlarged section on line C—D Fig. 1.

Fig. 4 is a reduced section on line E—F Fig. 2, said section being taken through the back end of the projectile.

Referring to the figures by characters of reference 1 designates the body of the projectile and in the front portion thereof is provided a chamber 2 for holding an explosive indicated at 3. A percussion pin 4 extends from the nose of the projectile to a cap in this chamber 2.

Arranged within the back portion of the projectile is a small chamber 5 for holding an explosive 6, there being a time fuse 7

leading to this chamber from the back end of the projectile and another time fuse 8 may be extended along the center of the projectile from the chamber 5 to the chamber 2.

60

Formed within the peripheral portion of the projectile and between the two chambers 2 and 5 are longitudinal slots 9. The back wall of each of these slots has its outer end portion overhanging a portion of the slot, thus to form a stop 10. Pivot pins 11 extend transversely of the slots close to the front ends thereof and mounted on each of these pins is a blade 12 normally housed within the slots. Each blade has an outwardly extending hook-like portion 13 the advancing edge of which is sharpened. When the blades are in their normal positions, these hook-like portions are housed within the slots and the blades are held against movement relative to the projectile by a restraining band 14 which extends around the projectile and has its outer face flush with the surface of the projectile. Extending from the chamber 5 are vent openings or passages 15 the outer ends of which are located directly back of the band 14 as shown particularly in Fig. 4.

75

When the projectile is discharged the time fuse 7 will be ignited and after a short flight the explosive in the compartment 5 will be ignited. The expansion of the gases will result in their rupturing the band 14 which will thus be thrown off of the projectile, thereby releasing the blades 12. As 90 the projectile is rotated rapidly while in flight, due to the rifling of the cannon, the blades 12, as soon as released from the restraining action of the band 14, will be swung outwardly by centrifugal force until 95 the free ends of the blades come against the stops 10. The blades will be held in their outwardly extended positions, the hooks 13 projecting beyond the periphery of the body of the projectile, as shown by dotted lines in Fig. 1. Consequently should the projectile pass through any wire entanglements, these hooks will engage the wires and sever them. The shell is designed to explode on contact with the ground, but should the percussion 100 pin fail to act, the time fuse 8 will ultimately cause the shell to explode.

105

Instead of having the passages 15 lead to the restraining band 14, as shown in Fig. 4, they can be extended through the inner walls 110

of the slots 9 at points remote from the pivots 11 so that, when the charge 6 is exploded, the force of the explosion will be directed against the inner faces of the blades 12 with 5 the result that said blades will be thrown outwardly thereby breaking their restraining bands and overcoming any tendency to remain seated in the slots as, for example, when the projectile is traveling a long distance.

10 Furthermore, if desired, the blades 12 can be pivotally mounted at their rear ends instead of their front ends or, in other words, can be reversed from the positions illustrated in Fig. 1. These modified constructions are so obvious that it is not deemed necessary to describe or illustrate them in detail.

15 What is claimed is:—

20 1. The combination with a projectile body, of members pivotally mounted in the body and adapted to swing outwardly therefrom in planes radiating from the body, a restraining means extending around the body 25 and members to hold said members housed within the body, an explosive charge for removing the restraining means from the body to release the members, and a time element for igniting the charge.

25 30 2. A projectile having a longitudinal slot, a member pivotally mounted within the slot and adapted to be projected therebeyond by centrifugal force during the rotation of the projectile, a band encircling the projectile 35 and holding said member within the slot, an explosive within the projectile, there being a vent leading therefrom and normally sealed

by the band, and a time fuse leading to the explosive.

3. A projectile having a longitudinal slot, 40 a member pivotally mounted within the slot and adapted to be projected therebeyond by centrifugal force during the rotation of the projectile, a band encircling the projectile and holding said member within the 45 slot, an explosive within the projectile, there being a vent leading therefrom and normally sealed by the band, a time fuse leading to the explosive, a second explosive charge contained within the projectile, a time fuse connecting the same to the first named explosive, and a percussion pin leading to said explosive charge.

4. The combination with a projectile body having radial longitudinal slots, of blades 55 pivotally mounted in the respective slots, outstanding cutting hooks upon the blades and normally housed in the slots, a band encircling the projectile and constituting means for holding the hooks and blades 60 within the slots, timed means for removing the band and releasing the blades, said means including an explosive charge within the projectile, there being a vent leading therefrom and sealed by the band, and a time fuse 65 leading to said charge.

In testimony that I claim the foregoing as my own, I have hereto affixed my signature in the presence of two witnesses.

EMMET JOPLING BONDURANT.
